UNITED STATES PATENT OFFICE.

FRED H. WHITE, OF TOLEDO, OHIO.

INDICATOR DEVICE.

Application filed February 23, 1928. Serial No. 256,284.

This invention relates to a device for reminding drivers of automobiles when it will be necessary for the oil in the crank case to be changed, although broadly, the invention is useful in connection with any motor driven vehicle utilizing a device for indicating the mileage traversed; and an object of the invention is to provide a simple and efficient device of the above character having the new and improved features of construction and arrangement hereinafter described.

The invention is shown by way of illustration in the accompanying drawings, in which:

Fig. 1 is a front elevation of an indicator device of the above character to serve as a reminder when the crank case oil should be changed; and

Fig. 2 is a transverse sectional view on the line 2—2 of Fig. 1 on an enlarged scale.

Numerous devices have heretofore been utilized for forcibly bringing to the attention of the automobile driver the necessity of changing the oil in the crank case at certain definite intervals. Stickers have been employed for this purpose, and these have usually been attached to the speedometer or windshield, and serve to call the driver's attention to the fact that when a certain mileage is indicated on the speedometer the crank case oil should be changed. These devices materially detract from the appearance of the automobile, and not infrequently become loose, or are torn or disfigured so that their effectiveness is seriously impaired.

The illustrated embodiment of this invention comprises a panel 1 having openings 2 at opposite ends to enable the same to be attached by screws to the instrument board of an automobile. The panel 1 may be of a relatively light weight sheet metal construction, and may be suitably ornamented as desired. Under some circumstances, it may be desirable to impress or otherwise display the name of a certain concern, so that it will serve as an advertising medium. As shown in Fig. 2, the rim portion 3 of the panel is turned inwardly so as to space the front of the panel a short distance away from the mounting. The form of panel shown is of elongated, substantially rectangular form.

Connected to the back of the panel 1 are a plurality of discs 4, which are secured in place by rivets 5 extending through the cen-

ter thereof. These discs may be of celluloid or similar material, and the central portion thereof is bowed or otherwise suitably curved, as indicated at 6, so that when the rivet is in place the body portion of the disc 60 is urged into engagement with the panel or adjacent disc. By this means the discs are held in place, and liability of accidental movement is reduced to a minimum.

As shown, the distance between the rivets 65 5 is slightly greater than the radius of the discs, and as shown, the discs are arranged in overlapping relation. In this instance five discs are employed and are arranged in such a manner that a portion of one disc 70 overlaps the adjacent disc, with the exception of the extreme right hand disc (Fig. 1), the entire surface of which is in engagement with the panel 1.

On each disc 5 in inwardly spaced relation to the marginal edge is an annular row of numbers 7, from zero to nine. Formed in the outer edge of each disc is a series of notches 9, one of the numbers 7 being positioned between a pair of notches. 80

Formed in the upper portion of the panel 1 is a longitudinal row of openings 9, an opening 9 being provided for each disc. These openings are so arranged that the numbers on the discs 4 are visible therethrough so that the several discs may be rotated to display the numbers desired, and this will indicate to the automobile driver when the mileage of the automobile reaches the number displayed, the oil in the crank 90 case should be replenished or changed.

As shown on the drawing, the number 12375 is displayed through the openings 9, and this will indicate that when the mileage on the speedometer reaches 12375, the oil in 95 the crank case should be changed. It is manifest that this device will serve as a constant mind aggravator which will constantly provoke the driver's attention and compel him to change the oil.

For turning the discs 4, a series of arcuately shaped slots 10 are formed in the lower portion of the panel 4, one slot being provided for each disc 4. These slots are arranged to register with the notches 8 in the discs, and are slightly greater in length than the distance between adjacent notches. When it is desired to change the number displayed in the opening 9, a pin or sharp pointed tool 105 may be inserted through the arcuately 110

shaped slots 10, and a disc engaged, and by moving the pin or tool in one direction or the other, corresponding movement is imparted to the disc.

5 The notches 8 are positioned at suitably spaced intervals, and as above pointed out, centrally aligned with the spaces between the numerals, the spaces between the numerals and between the notches being of 10 equal length.

While I have shown and described a construction which is the best form known to me at the present time, it will be understood that numerous changes in details of construction and arrangement may be effected without departing from the spirit of the invention, especially as defined in the appended claim.

15 What I claim as new and desire to secure by Letters Patent is:

20 In an indicator, a panel having a series

of sight-openings, a series of closely arranged discs of flexible resilient material on said panel disposed in overlapping relation, a central raised portion on each disc extending 25 away from said panel, means connecting said raised portion and panel, thereby yieldingly to urge said discs into engagement with the panel, said discs being associated with the respective openings and each having spaced 30 numerals thereon visible through the sight-openings, said panel having a series of openings, one for each disc formed to receive a pin or the like, each disc having a series of spaced pin-point receiving parts disposed 35 centrally to align with the spaces between the numbers and being spaced apart distances equalling the spaces between numerals.

In testimony whereof I have hereunto signed my name to this specification.

FRED H. WHITE.
